UNITED STATES PATENT OFFICE

WILHELM FRIEDRICH, OF BERLIN-LANKWITZ, GERMANY

DRY FIRE EXTINGUISHER CONTAINING A PRESSURE-GAS CYLINDER

Application filed May 11, 1927, Serial No. 190,541, and in Germany February 7, 1927.

My invention relates to fire-extinguishers wherein powder is expelled by gas under pressure, more particularly carbonic acid gas.

5 According to the present invention the gas cylinder is housed in a chamber disposed inside the container for the extinguishing powder, which chamber is accessible from the exterior of the said container and can be sealed.

10 When the gas cylinder is opened, the gas escapes first into the chamber surrounding the said cylinder and then passes in the form of a number of jets from the chamber into the extinguishing powder container causes 15 the powder to be broken up mainly against the walls of the powder container, imparting a swirling movement to the powder so that it is mixed with the gas and issues from the discharge nozzle of the powder container 20 in the form of a cloud.

In order that the invention may be the better understood drawings are appended illustrating two different forms of the invention, in which

25 Fig. 1 is a section through the longitudinal axis of the invention apparatus, which at the same time also passes through the chamber serving for the reception of the compressed gas cylinder. Fig. 2 is a top plan view with a section through the safety valve. Fig. 3 is a lateral elevation of a part of the chamber serving for the reception of the gas cylinder and shows the opening in the wall through which the gas passes from 30 this chamber into the powder chamber. Fig. 4 is a cross section through the intermediate chamber on enlarged scale viewed from above.

35 Fig. 5 shows a half longitudinal section of the upper half of the chamber for the gas cylinder also to a larger scale.

Fig. 6 shows a longitudinal section and Fig. 7 a front view of a guard for the powder container.

40 Fig. 8 a cross section on line VIII—VIII Fig. 1.

Referring to Figs. 1 to 8 of the drawings, the container 1 for the powder has at its upper end an opening closed by means of a screw cap 2 for the introduction of the pow-

der, and at its lower end a nozzle 3 through which the powder is discharged. Running longitudinally of and within the powder container 1 and spaced away from the wall thereof, preferably along the front side, that is above the nozzle 3, is a chamber 4 containing the gas cylinder 5. Brackets 4' co-operate with the lower end of the chamber 4 to position the same. This chamber 4 is closed at its lower end, but has an opening at its upper end closed by a screw cap 6 operable from the outside of said chamber and on which is a square plug or key 7 provided with a hand wheel 8, suitable provision being made to prevent the escape of the gas at this point. The key 7 engages a slot provided in a screwed stopper 9 of the gas cylinder 5, and the stopper 9 can be opened and closed by means of the key 7 by turning the handwheel 8. At its lower end the gas cylinder 5 is provided with a projection 10 which engages a perforation in a plate 11 disposed within and at the lower end of the pressure chamber 4 in a manner as to prevent the cylinder 5 turning with the stopper 9 when the latter is turned. A spring 12 at the base of the chamber 4 holds the cylinder and presses it upwards, so that the key 7 always engages with the slot of the stopper 9.

45 In order to loosen the powder in the powder container 1 and to eject it through the nozzle 3, openings 13 are provided in the walls of the chamber as shown clearly in Fig. 3, said openings being covered by a leaf spring in such a way that they are kept closed by the said spring in order to prevent the powder from entering the chamber, said spring however being operated to uncover the openings under the pressure of the gas from chamber 4, and permitting the gas to 50 pass out in several separate jets. The discharge openings 13 together with their covering spring or springs, as the case may be, are arranged in such a way that all the jets when 55 passing into the powder container 1 are led in the same lateral direction and in such a way that the gas must pass through the intermediate space between the walls of the powder container 1 and the chamber 4 in sepa- 60 65 70 75 80 85 90 95 100

rate jets as indicated by the arrow 14 in Fig. 8.

When, as aforesaid, a single covering member is provided for all the gas openings, the arrangement may comprise a steel band 15, Figs. 3 and 4 which covers all the openings 13 and is so arranged as to be slidable into position from above into a covering or housing 16 which is formed as a circular shaped pocket, as shown in Figs. 3, 4, and 8. Openings 17 are provided in this pocket 16 coincident with the openings 13, whilst the whole of the rear rim and the uncut portion of the front rim are secured by riveting, welding, soldering, or any other convenient manner to the chamber 4. When the spring band 15 is in position it covers all the discharge openings 13 of the chamber 4 and is lifted slightly at the discharge openings 13, when there is any pressure in the chamber 4, so as to allow the gas to issue through the openings 17 of cover 16 in the shape of separate fan-shaped jets. As the emission from all the jets is directed towards the same side, and the discharge openings are preferably disposed somewhat in front of the point where the walls of the powder container and the gas chamber 4 are closest together, the gas jets must pass through this intermediate space, as shown by the arrow 14, Fig. 8, and then circulate along the inner wall of the powder container 1, thus loosening and stirring up the powder against the wall of said container 1. The powder thus stirred up is then ejected together with the gas in the form of a cloud through the nozzle 3.

In order to ensure against there being too great a pressure in the chamber 4, the cover 6 of same is provided with a recess 18 which is sealed by means of a thin plate 19 of sheet copper or the like soldered on the inside. The thickness of this sheet copper is such that the plate 19 is ruptured or actually torn out when the internal pressure of the chamber 4 rises above the desired point, thus allowing gas to escape to the atmosphere. All risk of the chamber 4 bursting under excessive pressure is therefore avoided.

The powder container 1 is likewise protected against excess of pressure by a mushroom shaped safety valve 20, Fig. 2, which is held firmly pressed by a spring 21 against the valve seat 22 in the wall.

For the further protection of the powder container 1, an opening 23 (Figs. 1, 6 and 7) is provided in the walls thereof, preferably at the bottom on the side which is located above the discharge nozzle 3, and covered by a securely soldered safety plate 24 made of thin metal sheeting copper for example. The powder container 1 is thus provided with a two-fold protection against excess pressure, namely, the safety valve 20 and the excess pressure plate 24. This excess pressure plate 24 is situated above the discharge nozzle 3.

When the plate 24 is ruptured, an extinguishing jet of powder and gas issues from the opening 23 and thus assists the effect of the extinguishing jet from the nozzle 3, consequently the fracture of this excess pressure safeguard 24 does not interfere with the apparatus in its extinguishing work when it is in active use.

What I claim is :

1. A dry fire extinguisher comprising a powder container, a closure therefor, a container for gas under pressure, a closure for said container, a chamber disposed longitudinally within said powder container for said gas container, the chamber being spaced from the wall of said powder container, a closure for said chamber, means for admitting said gas from the gas container to the chamber containing said gas container, openings disposed at intervals along the chamber means cooperating with said openings for causing a substantially unidirectional, circumferential flow of gas around said wall and a nozzle upon said powder container for the discharge of the powder.

2. A dry fire extinguisher comprising a powder container, a closure therefor, a container for gas under pressure, a closure for said container, a chamber disposed within the powder container, the chamber being spaced from the wall of said powder container, said gas container having an opening, a screw plug for said opening, means operable from the exterior for operating said plug to control the passage of gas from the gas container to the chamber containing it, means for preventing the rotation of said container when the plug is operated, openings disposed at intervals along the chamber for the passage of the gas, deflector means cooperating with said openings for causing a substantially circumferential flow of gas around said wall and a nozzle upon said powder container for the discharge of the powder.

3. A dry fire extinguisher comprising a powder container, a closure therefor, a container for gas under pressure, a closure for said container, a chamber disposed within and longitudinally of said powder container for said gas container the chamber being spaced from the wall of said powder container an opening in the gas container, a screw plug for said opening, means operable from the exterior for operating said plug to control the passage of gas from the gas container to the chamber containing the same, means for preventing the rotation of the said container when the plug is operated, openings disposed at intervals along the chamber between said chamber and the powder receptacle, said openings being disposed adjacent the wall of the powder container and arranged to cause the issuing gas jets to sweep round the wall of said powder container in one direction,

and a nozzle upon said powder container for the discharge of the powder.

4. A dry fire extinguisher comprising a powder container, a closure therefor, a container for gas under pressure, a closure for said container, a chamber disposed within and longitudinally of said powder container for said gas container, the chamber being spaced from the wall of said powder container, said gas container having an opening, a screw plug for said opening, means operable from the exterior for operating said plug to control the passage of gas from the gas container to the chamber containing the same, openings disposed at intervals along the chamber and arranged to cause the issuing gas jets to sweep round the walls of said powder container in one direction for the discharge of the powder, said openings being disposed adjacent the wall of the powder container a plate supporting said gas container, a perforation in said plate, a projection on said container extending into said perforation and engaging said plate, and a spring to press said container upwards to maintain the engagement of the plug with its operating means.

5. A dry fire extinguisher comprising a powder container, a closure therefor, a container for gas under pressure, a closure for said container, a chamber disposed within and longitudinally of said powder container for said gas container, the chamber being spaced from the wall of said powder container; said gas container having an opening, a screw plug for said opening, means operable from the exterior for operating said plug comprising a screw plug mounted in the cover of the chamber, means for manually operating said plug, a projection on the inner end of said plug, a recess in the plug in the gas container for receiving the projection on the first plug whereby the passage of the gas from the gas container is controlled, means for preventing the rotation of the said container when the plug is operated, openings arranged at intervals along the chamber, said openings being disposed adjacent said wall of said powder container to cause gas jets to sweep round the wall of said powder container in one direction, and a nozzle upon said powder container for the discharge of the powder.

6. A dry fire extinguisher comprising a powder container, a closure therefor, a container for gas under pressure, a closure for said container, a chamber disposed within and longitudinally of said powder container for said gas container, the chamber being spaced from the wall of said powder container, said gas container having an opening, a screwed plug for said opening, means operable from the exterior for operating said plug to control the passage of gas from the gas container to the chamber containing it,

openings disposed at intervals longitudinally of the said chamber, resilient means closing said openings to prevent the passage of the powder, but yieldable to permit the passage of the gas and arranged to cause the issuing gas jets to sweep round the wall of said powder container in one direction, and a nozzle for the discharge of the powder.

7. A dry fire extinguisher comprising a powder container, a closure therefor, a container for gas under pressure a closure for said container, a chamber within said powder container for said gas container, the chamber being spaced from the wall of said powder container a closure for said chamber, means for admitting gas from said gas container to said chamber, openings disposed at intervals along the chamber and arranged to cause gas jets to sweep round the wall of said powder container in one direction, a nozzle upon said powder receptacle, an opening in the wall of said powder container, a frangible disc closing said opening and adapted to be broken under excessive pressure of the gas.

8. A dry fire extinguisher comprising a powder container, a closure therefor, a container for gas under pressure, a closure for said container, a chamber disposed within and longitudinally of said powder container for said gas container, the chamber being spaced from the wall of said powder container, said gas container having an opening, a screw plug for said opening means operable from the exterior for operating said plug to control the passage of gas from the gas container to the chamber containing the same, openings disposed at intervals longitudinally of the said chamber, resilient means closing said openings to prevent the passage of the powder, but yieldable to permit the passage of the gas said means cooperating with said openings to cause the issuing gas jets to sweep round the wall of said powder container in one direction, a nozzle for the discharge of the powder, and a spring valve upon the powder container for the escape of the gas should same exceed the desired pressure limits.

9. A dry fire extinguisher comprising a powder container, a closure therefor, a container for gas under pressure, a closure for said container, a chamber disposed within and longitudinally of said powder container for said gas container, the chamber being spaced from the wall of said powder container, said gas container having an opening, a screw plug for said opening, means operable from the exterior for operating said plug to control the passage of gas from the gas container to the chamber containing the same, openings disposed at intervals longitudinally of said chamber and adjacent said wall of said powder container, resilient means closing said openings to prevent the passage of the powder, but yieldable to per-

4

mit the passage of the gas, said means comprising a thin strip of material, a longitudinally disposed pocket upon the outside of the wall of the chamber, openings at one side of said pocket for the escape of the gas when the strip is raised under the pressure of said gas whereby the issuing gas is caused to sweep round the wall of said powder container in one direction and a nozzle for the discharge of the powder from said powder container.

In testimony whereof I have affixed my signature.
